UNITED STATES PATENT OFFICE.

FRANK H. KISER, OF LATROBE, PENNSYLVANIA.

MAIL-BAG-DELIVERY DEVICE.

1,257,714.

Specification of Letters Patent. Patented Feb. 26, 1918.

Application filed July 7, 1917. Serial No. 179,172.

To all whom it may concern:

Be it known that I, FRANK H. KISER, a citizen of the United States, residing at Latrobe, in the county of Westmoreland and State of Pennsylvania, have invented certain new and useful Improvements in Mail-Bag-Delivery Devices, of which the following is a specification.

This invention relates to railway mail bag delivering devices and has for its principal object to provide a strong, simple and sure means for collecting, holding and locking in position after collection from a passing mail car, mail sacks collected therefrom while the train passes.

A further object of the invention is to provide in a mail sack collecting device a stationary upright support placed beside the railway track, on the top of which is carried a horizontal bar rotatable in bearings and provided with a projecting arm bent into such shape as will readily gather the mail sacks projected from the mail car, and after so collecting the sacks to swing downwardly and engage locking means that will hold the sack from falling or from accidental displacement.

With the above as the principal objects in view, the invention consists in the novel construction, combination, and arrangement of parts hereinafter described, pointed out in the appended claims and illustrated in the accompanying drawing, in which:

Figure 1 is an elevation of the improved mail bag collecting device in position to receive a mail sack from a passing mail car.

Fig. 2 is a horizontal sectional view on the line 2—2 of Fig. 1, and

Fig. 3 is a detailed view in section of the upper portion of the collecting device on the line 3—3 of Fig. 2.

In the drawing, 10 indicates a portion of a railway mail car within which near the door 11 is mounted a crane 12 comprising a vertically located post 13 from which project two spaced horizontal arms 14 and 15 on the ends of which are holding means 16 for supporting the mail sack 17 in position to be collected when the crane is swung outwardly from the side of the car, as shown in Fig. 1. A handle 18 projects from the post 13 for swinging the crane.

At the side of the railroad track and at a suitable distance therefrom are erected two vertical posts 19 and 20, disposed in the line of the track and each having secured

to its upper end on the side adjacent the track a bearing 21 within which bearing is mounted a horizontal rocking bar or shaft 22, said bar also having limited longitudinal movement in its bearings. Fixed to one end of the rocking bar 22 is a mail bag collecting arm 23 adapted when in operative position to extend toward the car in a horizontal plane and when in inoperative position to hang downwardly as in dotted lines, Fig. 3. The collecting arm 23 is formed with a loop 24 extending from the point of attachment of said arm to the rocking bar in the direction of movement of the passing car, the outer part of said loop forming the principal part of the arm 23 extending in the opposite direction and at an angle to the bar for a sufficient distance to easily grasp a mail sack suspended from the crane of a car. The outer end of the arm 23 is bent or turned backwardly upon itself for a short distance and lies parallel to the rocking bar 22 as clearly shown at 25. Projecting from the rocking bar on the side opposite the arm 23 is a finger 26. A second finger 27 projects from the same side of the rocking bar near its opposite end, the distance between said fingers being less than the distance between the posts 19 and 20 for a purpose to be described later.

A pin 28 projects from the post 19 toward the post 20 at such a point that when the arm 23 is swung into horizontal position and the rocking bar 22 moves endwise toward the post 19, the finger 26 will pass under the pin 28 and hold the arm 23 extended in horizontal position for collecting the mail sacks. In this position the finger 27 will be spaced a short distance from the post 20.

Below the bearing 21 on post 19 is a bracket 29 in which is mounted a pivoted pawl 30 that normally stands in vertical position and is so maintained by gravity or by resilient means as may be desired. The distance of this pawl from the bearing 21 is such that when the arm 23 swings downwardly, the terminal end 25 thereof will strike the pawl and, tilting the same, come to rest in the dotted position shown in Fig. 3. The pawl returning to its upright position holds the arm against outward movement by engaging with a stop 31.

In operation the arm 23 is swung into horizontal position as shown in the drawing to receive a mail sack 17 extended from

the crane 12 of a passing car. As the car passes, the mail sack engages the arm and is withdrawn from the crane, the force causing the rocking bar 22 to move end-
wise in the direction of the moving crane
until the finger 27 strikes the post 20. This
movement of the bar is sufficient to withdraw
the finger 26 from the pin 28, where-
upon the weight of the arm and mail sack
swings the bar 22 carrying the arm down-
wardly to dotted position and lock the same
in engagement with the pawl 30.

This invention is simple, strong and is
made of few parts, is self-acting and not
liable to become deranged by use or ex-
posure to the weather, and by mounting the
post 19 in concrete foundation a rigid and
immovable structure will be provided and
will require practically no care or attention
to keep the same in operative condition.

I claim:

1. A mail bag collecting device comprising
a support formed of two upright posts disposed
in line with a railway track at the
side thereof and a bearing at the upper end
of each of said posts, a horizontal bar rotat-
ably and longitudinally mounted in said
bearings, a mail bag collecting arm project-
ing from said bar near one end thereof and
having a bag holding loop therein, spaced
fingers on said bar to limit the longitudinal
movement of the bar by engagement with

said posts, a pin projecting from one of said
posts adapted to engage one of the fingers
and hold the collecting arm in horizontal
position, and locking means on one of said
posts for holding said arm in its downward
position. 35

2. In a mail bag collecting device, the com-
bination with two vertical posts disposed in
line with a railway track and at the side
thereof, and a bearing on the upper end of
each of said posts, of a horizontal bar rotat-
ably and longitudinally movable in said
bearings, an arm projecting from one end
of said bar having a pocket therein to re-
ceive the mail sack and a locking tooth on
its outer end, spaced fingers projecting from
the bar between said posts and limiting lon-
gitudinal movement of said bar, a pin pro-
jecting from one of said posts adapted to
engage the adjacent finger on said bar and
hold the arm in horizontal position for col-
lecting a mail sack, and a locking pawl on
one of said posts for engaging the tooth on
said arm and holding the latter in a de-
pressed position when released from the
holding action of said pin and finger. 40 45 50 55

In testimony whereof I affix my signature
in presence of two witnesses.

FRANK H. KISER.
